UNITED STATES PATENT OFFICE.

EUSTACHIO GUARDIANI, OF PHILADELPHIA, PENNSYLVANIA.

FLY SCREEN FOR WINDOWS.

Application filed July 13, 1922. Serial No. 574,706.

To all whom it may concern:

Be it known that I, EUSTACHIO GUARDIANI, a citizen of the United States, residing at Philadelphia, in the county of Philadelphia and State of Pennsylvania, have invented certain new and useful Fly Screens for Windows, of which the following is a specification.

My invention relates to window screens and more particularly to an adjustable screen to fit beneath the raised lower sash of a window.

The purpose of my invention is to provide an improved screen of the character indicated adapted to easy and inexpensive manufacture and to adequately meet the needs of service.

A further purpose is to provide the screen with a safety device so that if a child leans against it there may be no danger of the screen suddenly giving way and of the child possibly falling through the window.

A further purpose is to have this safety device comprise support against the bottom of the raised lower sash at the top and support against the window strip in front of the screen at the bottom.

A further purpose is to provide a pair of intersliding screens adapted to fit beneath a raised lower sash with improved connection between the mesh and frame of each screen, in which the mesh is clamped to advantage by the frame parts of the screen.

Further purposes will appear in the specification and claims.

I have preferred to illustrate my invention by but one type, selecting a form that at once well illustrates the principles of my invention and adequately meets the needs of actual service.

Figure 1 shows my invention in front elevation.

Figure 2 is a section through the line 2—2 of Figure 1.

Figure 3 is a detail section to enlarged scale through the line 3—3 of Figure 1.

Figure 4 is a detail section to enlarged scale through the line 4—4 of Figure 1.

Figure 5 is a detailed section to enlarged scale through the line 5—5 of Figure 1.

Figures 6, 7, 8 and 9 are broken end elevations at the respective corners of Figure 1 but to slightly enlarged scale, and illus-

trate the construction of the frame at the outer corners.

In all drawings like numerals refer to like parts.

Referring to the drawings and describing in illustration and not in limitation,

My improved screen comprises outer and inner screens, 15 and 16 respectively, that interslide to fit between the vertical slide ways 17, 18 of the raised sash 19, rails 20, 21 of the inner screen sliding in the mating channels 22, 23 of the outer screen.

I have preferred to show both the channel members upon the outer screen and both the rail members upon the inner screen, rather than the rails upon either outer or inner screen, or a combination of these, as it makes a very neat assembly of the parts.

Prior to my invention, the convenience of the sliding screens that fit beneath the raised lower sash has been offset by an element of danger incident to their use with children, in that when leaned against by children they are likely suddenly to give way outwardly with incident danger and general annoyance from having to replace them.

To avoid this objection to their use I support the screen from displacement outward by an upward projection 24 from the intermediate side 25 of the inner screen extending it partially across the bottom of the raised sash 19, thus preventing the top of the screen from yielding to an outward push, and by an inward hook 26 from the intermediate side of the bottom of the inner screen slidably hooking over the window strip 27 in front of the screen.

Normally the sides of the screen next the window are supported along their whole length, and consequently at top and bottom, by the vertical slide-ways 17, 18, of the sash, but experience has shown that in use this type of screen very frequently works free from the slide-ways, and in view of this

I also preferably provide upward projections 28, 29 respectively from the sides of the screens adjacent the window. These projections, like projection 24, extend partially across the bottom and support the top corners of the screen from yielding to any outward push; likewise at the bottom I preferably provide the inward hooks 30, 31 from near the lower corners of the screen to hook over the window strip 27.

The hooks 31, 31 and the upward projections 28, 29 are sufficiently spaced from the sides to clear the slide-ways 17, 18 of the sash.

5 In order to avoid undue motion of the individual screens after they have been fitted to place I provide the hook of the outer screen and one of the hooks of the inner screen, with screws 32, 33 adapted to clamp 10 the respective screens to the window strip 27, as seen in Figure 5.

My invention comprises not only these safety devices but also the improved connection of the mesh to the frame of the 15 screens.

The vertical sides 34, 35 respectively at the slide-ways 17, 18 are of wood and are saw-cut longitudinally at 36, the mesh 37 being inserted into the saw-cuts and clamped 20 there by nails 38.

At the intermediate vertical sides 39, 40 of the inner and outer screens I clamp the mesh between wooden strips 41, 42 and metal angles 43, 44 as best seen in Figure 3, and 25 on the inner screen I extend the flattened side 45 of the angle 43 above the screen to form the supporting projection 24. The side flange of the angle in Figure 3 supports the angle, and hence the fastening screws, 30 against the strip 42, to take the strain of the mesh toward the left in that figure.

Along the channel and rail members of the individual screens I make connection to the mesh as best seen at 46, 47 of Figure 5. 35 The channel is nearly all made of wood, in two parts 48, 49 and these parts are nailed together with the mesh between them. In Figure 5, 50 is the outer edge of the angle 44 of the outer screen, the other side of the 40 angle being cut away at the end of the strip 42, best seen in Figure 3.

The rail member comprises a wooden member 51, preferably substantially symmetrical, upon one side 52 of which the mesh is 45 clamped by a metal flat or strip 53.

The vertical sides 34, 35 are conveniently provided with handle cuts 54, 55 as seen in Figures 1 and 4.

The framing between the vertical and 50 horizontal members of the individual screens is shown in Figures 6 to 9. Between a vertical member and a channeled member the framing is constructed as seen in Figures 6 and 7, the vertical member being notched at 55 56, 57 and plowed at 58 to fit the channel, which is cut away at the side for the tenon of the vertical member. A vertical member and a rail member are half notched as shown in Figures 8 and 9, the rail portion of the 60 rail member being cut away and the vertical member suitably notched to fit.

In view of my invention, variations and modifications to meet individual whim or particular need will doubtless become evident to others skilled in the art and I claim 65

all such variations and modifications in so far as they fall within the reasonable spirit and scope of my invention.

Having thus described my invention, what I claim as new and desire to secure by Letters Patent is:

1. In an adjustable intersliding window screen adapted to fit in a window beneath a raised lower sash and in combination with the window casing, an inner and an outer screen adapted to interslide and to be relatively spread to fit between the vertical runways of the sash, a window strip across the window in front of the bottom of the screen, an inwardly projecting hook from the intermediate lower corner of the inner screen slidably interlocking with the strip to prevent the bottom of the screen from being pushed outward and a screw in the hook adapted to engage the strip and thereby clamp the inner screen to the strip. 75

2. In an adjustable intersliding window screen adapted to fit in a window beneath a raised lower sash, four vertical end bars, upper and lower horizontal slidable strips having rail and channel connection, the channel strips being divided vertically into two parts with screen wire clamped between the two parts and secured to the end bars and strips retaining the screen wire against the faces of the rail flanges, on the sides of said flanges toward the rail heads. 90

3. In an adjustable intersliding window screen, four vertically arranged end bars, wire netting therefor and upper and lower interfitting pairs of sliding strips, completing the screens, each pair comprising a channel member and a rail having a flange and a head, the channel members divided lengthwise of the channel to hold the screen wire and strips retaining the screen wire against the flanges of the rails. 100

4. In a screen forming one of a sliding pair of window screens, vertical end bars and horizontal guide bars, the guide bars 110 being of channel shape and having one flange each removable from the bottom of the channel in combination with screen wire fastened to the vertical end bars and clamped between the removable channel members and the remainder of the channel members. 115

5. In a screen forming one of a sliding pair of window screens, vertical end bars and horizontal guide bars, the guide bars 120 comprising heads adapted to fit in the channels of the other screen of the pair and flanges adjoining the heads and having faces toward the heads in combination with screening secured to the end bars and strips holding the screening to those sides of the flanges toward the heads. 125

6. In an adjustable intersliding window screen adapted to fit in a window beneath a raised lower sash, an inner and an outer 130

screen intersliding to fit between the vertical runways of the sash, the slidingly interlocking members comprising rails and mating channels, the channel being of wood and longitudinally two-part, the line of division substantially vertically along the channel bottom and the mesh of the screen being clamped between the parts.

7. In an adjustable intersliding window screen adapted to fit in a window beneath a raised lower sash, an inner and an outer screen intersliding to fit between the vertical runways of the raised sash, the slidingly interlocking members comprising horizontal rails and mating horizontal channels, each screen having exterior and interior vertical frame members, and the interior vertical members each comprising a wooden strip and a metal angle clamping

20 between them the mesh of the screen.

8. In an adjustable intersliding window screen adapted to fit in a window beneath a raised lower sash, an inner and an outer screen intersliding to fit between the vertical runways of the raised sash, the slidingly interlocking members comprising horizontal rails and mating horizontal channels, each screen having exterior and interior vertical frame members, and the

30 interior members each comprising a wooden

strip and a metal angle fitting about two sides of the strip clamping between them the mesh of the screen, the angle of the interior member of the inner screen being flattened at the top and extended upward above the top of the screen to support the top of the screen against the bottom of the raised sash.

9. In an adjustable intersliding window screen adapted to fit in a window beneath a raised lower sash, an inner and an outer screen intersliding to fit between the vertical runways of the raised sash, the slidingly interlocking members comprising horizontal rails and mating horizontal channels, a metal flat along the rail side of the bottom of each rail clamping the mesh of the screen to the rail and affording bearing surface for one side of the channel, the channels being of wood and longitudinally two-parts that clamp between them the mesh of the screen, exterior vertical frame members, one for each screen, longitudinally saw-cut and clamping the mesh of the screen in the saw-cut, and interior vertical frame members, one for each screen, and each comprising a wooden strip and a metal angle longitudinally clamping between them the mesh of the screen.

EUSTACHIO GUARDIANI.
